UNITED STATES PATENT OFFICE.

DONALD McDONALD, OF LOUISVILLE, KENTUCKY.

APPARATUS FOR HANDLING COKE.

942,341.

Specification of Letters Patent.

Patented Dec. 7, 1909.

Application filed August 9, 1905. Serial No. 273,417.

To all whom it may concern:

Be it known that I, DONALD McDONALD, a citizen of the United States, and a resident of Louisville, in the county of Jefferson, 5 State of Kentucky, have invented certain new and useful Improvements in Apparatus for Handling Coke, of which the following is a specification.

This invention relates more especially to 10 the handling of coke in gas plants, though the invention may be applied to any coke producing plant.

One object of the present invention is to handle the coke in such manner that quenching 15 may take place within the gas house without incident disagreeable effects or loss of time due to the presence of the steam or vapor generated in quenching, within and throughout the cellar and other parts of 20 the plant and to accomplish this result without the use of suction fans or other expensive special apparatus.

Another object of the invention is to quench the coke in such a manner as to improve 25 its quality and to lessen the wear and tear on the apparatus.

In carrying out my invention, I provide the bench of retorts with as many separate and independent bins of laterally restricted 30 area and with tight inclosing sides, and bottom closures, as there are retorts or vertical rows of retorts in the plant, and I so locate these receiving and confining bins that the contents of any retort or vertical row of retorts 35 may be thrown off into its own especial bin and there retained until quenching is complete; said bins being also so located beneath the floor of the gas house that the steam arising therefrom and which is laterally restricted by the confining sides, will be drawn inward toward and passed upward in front of the bank of retorts, being thus prevented not only from spreading over the cellar beneath the floor but prevented from 40 spreading over the working space on the gas house floor and thus permitting free access to and full activity throughout the plant and not even interfering with the recharging of the retorts immediately after drawing, 45 since the steam is prevented from condensing to anything like non-transparent condition until it rises above the hot area immediately in front of the retorts. I also provide means whereby the body of coke in

a given retort may be sprayed within the bin 55 and the steam generated from lower strata, even down to the bottom of the mass, is compelled to rise through the body of coke. I also provide means whereby the coke, after being quenched by the spraying operation 60 and dried by evaporation due to its own heat, may be discharged from the individual bin, into a suitable vehicle below and it will then be in condition to remain in the cellar without objection until the car is filled from other bins and moved off. This quenched and dried condition of the coke also permits the use of a cheap wooden car instead of a metal car which is necessary where the coke is dumped in hot state. 70

My invention will be fully understood upon reference to the accompanying drawings, in which—

Figure 1 is a vertical section showing a retort bench with the main floor, the cellar 75 beneath the floor, one of the individual bins mounted in the floor and a car in the cellar, beneath the bin in position to receive the contents of the bin. Fig. 2 is a plan view showing horizontal series of retorts or rows 80 of retorts and the bins in position to receive the contents thereof.

1 indicates retorts arranged in horizontal series and superposed in vertical rows, and 85 2 represents a horizontal series of bins, equal in number to the retorts or vertical rows of retorts in horizontal series and mounted in the floor 3 of the plant in such position that each bin will receive the contents of all the retorts of one vertical row. These bins are 90 thus necessarily of lateral restricted area and each is identified directly with the working sphere of its corresponding retort or vertical row of retorts. It is constructed with tight sides which not only confine the 95 body of coke therein to the steam generated in quenching, but limit the lateral dimensions of the column of steam which rises from the bin when the bin is open or which escapes around its upper closure if the bin is closed. The bin is preferably provided with a suitable top closure. I have herein shown doors 4 and 5 for this purpose which are hinged respectively at 6 and 7, said doors being particularly arranged for serving some additional functions, such for instance as a guide for directing the coke into the bin, for which purpose door 4 is pro-

vided with a rest 8, a limiting wall to prevent the coke from going beyond the bin, for which purpose door 5 is arrested in the position shown in dotted lines. But I 5 do not herein claim the details of these doors as the same form the subject matter of claims in my Letters Patent No. 832,693, granted October 9, 1906 upon an application of later date than my present case.

10 I desire it understood that in its broader aspect, my invention is not limited to the use of a top closure for the bin since such is not essential to a measurable attainment of the results aimed at. This top closure is, 15 however, a convenience and will be generally desirable for the reason that it provides a platform over which operatives may walk in serving the apparatus and with the otherwise tight bin closed at the top, an immediate steaming action on the coke is insured.

At its bottom, each bin is preferably constructed in the form of a chute which will insure discharge of the bins; that is, provided the car is not located directly beneath the bin; also with a suitable releasable bottom closure adapted to confine the coke until such time as quenching and drying have advanced to the proper stage or until it is desired to discharge the coke. To attain these 25 ends, the bin is preferably constructed with inclined fixed bottom 9 and with the movable bottom or door 10 hinged at 11 and releasably secured by latch 12. It will be seen that the bins depend into the cellar 13 and terminate at such a height that there 30 is ample space for the vehicle 14 to move into receiving position beneath them.

For the purpose of quenching, I have shown a spray pipe 18 suitably arranged 40 within the upper portion of the bin and supplied by pipe 19, some of the openings of this pipe being so disposed as to direct water upon sides of the bin to keep the bin cool and direct the water downward to the 45 lower strata of coke so as to supply the latter from the start and to avoid delay which would result where the water must trickle over the upper parts of the coke to reach the lower parts and is thus largely vaporized 50 in the upper portions before reaching the lower portions.

16 represents a gutter in the floor of the cellar which is covered by perforated plate 17, supported on the ties 17^a and preventing 55 the escape of coke into the gutter while permitting free access of surplus water to the gutter.

The method of putting my invention into effect is as follows: During the charging of 60 the retorts 1, the top closures of the bins, if employed, are closed to provide walking space. After the coal is sufficiently distilled or the gas is driven off, in a retort or vertical row of retorts, the top closure of the corresponding bin is opened, the coke is with-

drawn from the retort or row of retorts by a suitable puller or other apparatus and directed or otherwise caused to drop into the corresponding bin. The bin is then preferably closed and water is admitted through the pipe 19 to the sprayer 18 which directs the water on top of the piled coke and against the sides of the bin which sides direct the water downward, with the result of covering the sides and bringing the water 75 into contact with lower portions of the body of coke. This continues until the quenching is carried far enough, when the supply of water is cut off and the steaming action allowed to continue under the residual heat 80 of the coke until the coke is sufficiently dried, or by the evaporation further reduced in temperature, after which the contents of the bin may be discharged by opening the door 10 or other bottom closure. During 85 the quenching and drying operation, it is obvious that the column of steam (if the bin is open) or the area of the rising steam (if it escapes around cracks of the closure) will be restricted laterally by the sides of the 90 bin. It will also be observed that with the heated area immediately in front of the bank of retorts, which keeps up a constant upward current, the steam will be naturally thrown inward and further restricted within 95 the immediate working sphere of the given retort or vertical row of retorts and will thus not invade through portions of the working space or extend outward from the oven a sufficient distance to materially interfere with recharging the retorts at once 100 if it is desired so to do. Moreover, the high temperature of the area in front of the oven prevents condensation of the steam to a sufficient degree to obscure the view of the operative and thus renders the presence of the steam wholly unobjectionable. Little or no steam escapes from the bottom of the bin and it is thus convenient to manipulate the vehicle in the cellar at any and all times and discharge any bin, regardless of the stage of quenching in any other bin.

When the top closure is employed during the quenching operation, steam from the coke permeates thoroughly all portions of the body of coke, giving an improved color to the coke and insuring uniformity in the progress of the quenching action so that when discharged, the body of coke will be found to have been uniformly treated.

Having thus described my invention, what I claim as new and desire to secure by Letters Patent is:

1. The combination with the retort in a gas-retort house, and the floor of said house; of means for receiving, confining and quenching the coke from said retort, comprising a bin located at an opening in said floor beneath said retort; said bin being open at top to admit coke from the retort 125 130

and to permit vapor from the quenching water to escape vertically from the bin, being constructed with tight side walls to confine the body of coke being quenched as well as the vapor therefrom and limit the area of the rising vapor to the space in front of the retort discharging into the bin, and being provided with means for spraying the coke within it, and with a bottom closure movable to permit the quenched coke to pass from the bin.

2. The combination with the retort in a gas-retort house, and the floor of said house; of means for receiving, confining and quenching the coke from said retort, comprising a bin fixedly mounted at, and projecting downwardly from, an opening in said floor at a point beneath said retort; said bin being open at top to admit coke from the retort and to permit vapor from the quenching water to escape vertically from the bin, being constructed with tight side walls to confine the body of coke being quenched as well as the vapor therefrom and limit the area of the rising vapor to the space in front of the retort discharging into the bin and being provided with means for spraying the coke within it, and with a bottom closure movable to permit the quenched coke to pass from the bin.

3. The combination with the bench of retorts in a gas-retort house, and the floor of said house; of individual means serving to separately receive, confine and quench the coke from the several retorts, comprising bins fixedly located in and projecting downwardly from openings in the said floor beneath the several retorts; said bins being restricted in horizontal dimensions to the several spaces of the retorts which they respectively serve and being open at top to admit coke from the retort and to permit vapor from the quenching water to escape vertically from the bin, being constructed with tight side walls to confine the body of coke being quenched as well as the vapor therefrom and compel the rising vapor to escape above the floor in an area limited to the space in front of the retorts discharging into the bin; and said bin being provided with means for spraying the coke within it, and with a bottom closure movable to permit the quenched coke to pass from the bin.

4. The combination with a retort house having a horizontal series of retorts, a main floor and a cellar beneath the main floor, of a corresponding series of quenching bins located beneath said retorts and depending into the cellar below, each bin located and constructed to receive and to confine laterally the coke from the retort located above it, and each having a bottom closure.

5. The combination with a plurality of retorts, arranged in horizontal series, of a corresponding series of quenching bins be-

neath said retorts, each located and constructed to receive and confine the coke from the retort located above it, and each having a bottom and a top closure and provided with means for quenching the coke, located within the bin whereby the body of coke from a single retort may be quenched while completely inclosed and the vapors produced by the quenching prevented from spreading through the working spaces.

6. The combination with a horizontal series of coke retorts, of a corresponding series of quenching bins beneath said retorts, each located and constructed to receive and confine the coke from the bench located above it, and each having a bottom and a top closure and provided with means for quenching the coke, located within the bin whereby the body of coke from a single retort may be quenched while completely inclosed and the vapors produced by the quenching prevented from spreading through the working spaces, said spraying means being adapted to spray the sides of the bins to keep the same cool and to deliver quenching water to the lower portions of the body of coke.

7. In combination with the plurality of coke retorts arranged in horizontal series and conveying apparatus located at a lower level than the retorts; a series of separate, non-communicating and independently operable quenching bins corresponding in number to the retorts extending in horizontal series, located beneath the respective retorts, and each provided with an independent self-contained quenching means adapted to spray the body of coke, and with top and bottom closures whereby the coke is exposed not only to the spray but to a steaming effect whereby the body of coke from the retort above each bin may be treated separately from the coke drawn from all the other retorts and before discharging into the conveyor and thereby leaving the remaining doors and other bins free for independent manipulation and preventing the presence of vapor in the space surrounding the conveyor.

8. A plant comprising a series of coke or gas retorts, a series of chutes under said retorts, means for supplying water so that it may pass to the bottom of said chutes, said chutes being adapted to receive the charge of coke drawn from the adjacent series of retorts and being of such size and proportion as to hold the coke in a column and to confine the steam generated from water passing to the bottom thereof to cause it to rise through the column of coke.

9. A plant comprising a series of coke or gas retorts, a series of chutes under said retorts, means for supplying water to said chutes so that it may pass to the bottom thereof, said chutes being adapted to hold

the coke charge from the adjacent series of retorts in a column and to confine the steam generated from the water passing to the bottom thereof to cause it to rise through the 5 column of coke, and a closure for the lower end of the chutes adapted to permit a slow drain of water therefrom.

The foregoing specification signed at Louisville, Ky., this seventh day of August, 1905.

DONALD McDONALD.
